[57] CLAIM

The ornamental design for a seed caddy trailer, as shown and described.

DESCRIPTION

FIG. 1 is a perspective view of the seed caddy trailer showing my new design;

FIG. 2 is a right side elevational view thereof;

FIG. 3 is a top plan view thereof;

FIG. 4 is a left side elevational view thereof;

FIG. 5 is a bottom plan view thereof;

FIG. 6 is a rear elevational view thereof; and,

FIG. 7 is a front elevational view thereof.

The broken line showing of the auger discharge is included for illustrative purposes only, and does not form a part of the claimed invention.
